United States Patent Office

Des. 227,077

Patented June 5, 1973

227,077

BOTTLE

Salvatore Auditore, New York, N.Y., assignor to
G. Heileman Brewing Company Inc., La Crosse, Wis.

Filed Feb. 25, 1970, Ser. No. 21,605

Term of patent 14 years

Int. Cl. D9—28
U.S. Cl. D9—28

FIG. 1

FIG. 2

FIG. 1 is a front perspective view of a bottle showing my new design; and

FIG. 2 is a top plan view thereof.

The bottle is circular in all cross sections and the side opposite the side shown is substantially the same as the side shown.

I claim:

The ornamental design for a bottle, substantially as shown and described.
